UNITED STATES PATENT OFFICE.

JOHN F. OHMER, OF DAYTON, OHIO, ASSIGNOR TO OHMER FARE REGISTER COMPANY, OF ROCHESTER, NEW YORK.

TICKET ISSUING AND RECORDING MACHINE.

No. 890,170.

Specification of Letters Patent.

Patented June 9, 1908.

Application filed November 4, 1905. Serial No. 285,933.

To all whom it may concern:

Be it known that I, JOHN F. OHMER, a citizen of the United States, residing at Dayton, in the county of Montgomery and State of Ohio, have invented certain new and useful Improvements in Ticket Issuing and Recording Machines; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to improvements in ticket-issuing and recording machines, and comprises certain improvements of the ticket-issuing and recording machines shown and described in Letters Patent No. 779,557 of January 10, 1905, issued to John F. Ohmer and Elmer H. Bridenbaugh; and Letters Patent No. 789,333, of May 9, 1905, issued to John F. Ohmer.

The present invention consists in the bringing together in a unitary machine mechanism for properly issuing a ticket for a multiplicity of fares of different denominations. The ticket is of a single form which in this machine is made to subserve the purpose of a multiplicity of different tickets, thereby enabling the machine to be brought within a convenient size.

The essential features of the invention comprise means for feeding such tickets from a continuous strip; means for perforating said tickets at the desired points, thereby reducing each ticket to a specific ticket upon which is indicated the fare, the point of destination, the direction of travel, the month and the date thereof; means for maintaining a total count of the tickets issued from the machine; means for maintaining a detail count of each fare or ticket that is issued from the machine; means for bringing into an operative position each detail counter with each fare or ticket which is issued; means for bringing each detail counter into an operative position with the punch which perforates each fare in each ticket, and other mechanism hereinafter described and claimed.

Preceding a detail description of the invention, reference is made to the accompanying drawings, of which—

Figure 1, is a front elevation with the casing removed, showing the interior mechanism. Fig. 2, is a side elevation with the casing shown in section. Fig. 3, is a side elevation on the line $x-x$ of Fig 1. Fig. 4, 60 is a top plan view. Fig. 5, is a sectional view on the line $y-y$ of Fig. 1. Fig. 6, is a view of a form of ticket suitable to the machine. Fig. 7, is a horizontal section on the line $x-x$ of Fig. 3. Fig. 8, is a detail view of 65 the gearing between the detail counters and the main operating lever. Fig. 9, is a detail view of the shiftable actuator.

In a detail description of the invention, similar reference characters indicate corresponding parts.

While it is my purpose to give such a detailed description of the invention as will enable a clear understanding of the same, it is not my purpose to limit myself to such 75 details, but on the contrary, I desire to claim broadly means in a single machine which enables a single ticket to be utilized in connection with a multiplicity of different fares and different points of destination, and 80 means within said machine for keeping a separate and distinct count of each fare or ticket, and also means for keeping a total count of all the fares or tickets, and further means consisting of devices whereby each 85 ticket is individualized or made into a ticket showing a specific value of fare and a specific point of destination. These latter means consist in the present instance of a series of punches or perforators which are operated 90 during one movement of the main operating lever, but it will be understood that these ticket punches may be substituted by means for printing or impressing upon each ticket the value of the fare, the point of destination, 95 and other matter necessary to be shown or indicated.

The machine as shown in the accompanying drawings, comprises a suitable framework 1 which is inclosed in an exterior casing 100 2 of any suitable design. This frame-work has two divisions or compartments 3 and 4, in one of which the ticket-issuing and perforating mechanism is located, and in the other of which the detail counting mechanism is located. The figures on the peripheries of the detail counters may be raised and thereby made printing counters.

I will proceed to describe the first named mechanism—to-wit: the ticket issuing and 110

perforating mechanism which is common to some extent with the mechanism shown and illustrated in my former patents hereinbefore referred to. Suitably housed within the compartment 3 is a continuous roll of tickets 5, which tickets are of the form shown in Fig. 6, and the essential features of which are the different fares, the different points of destination, the month and the date thereof, and the direction of travel, all being printed in suitable groups in order that they may be brought within suitable proximity to the perforators or punches. The fares indicated on the tickets in the present instance are $\frac{1}{2}^{\text{p}}$ 1^{p} 2^{p} 3^{p} 4^{p} and 5^{p} , but it will of course be understood that the ticket strip may be provided with tickets of different denominations from those shown and with different points of destination.

From an inspection of the ticket, and from the foregoing description, it will be understood that a single ticket form is here made to answer the purpose of twelve different tickets or six different denominations of fares. This ticket strip is carried upwardly at the rear of the machine between two guide plates 6 and 7, which have suitable openings for the punches or perforators to be presently described, and said ticket strip is thence carried horizontally to the front of the machine through upper guide plates 8 and 9 which have suitable openings for the upper series of punches. The said ticket strip is fed forwardly by means of a feed roller 10 which has a series of peripheral serrations or ribs 11 which grip the body of the ticket strip. Coöoperating with this feed roller is a pressure roller 12 which insures a proper contact of the ticket strip. This pressure roller 12 is mounted upon a pivotal frame 13. The feed roller 10 is driven in its feeding operations upon each upward movement of a main operating lever 14 by means of a pinion 15 which is on the shaft 16 of said roller, and a large spur wheel 17 which is on the main operating shaft 18. The ratio of movement is five revolutions of the pinion 15 to one of the spur wheel 17. The lever 14 is loose upon the shaft 18 and is enabled to turn said shaft in the feeding operations by means of a ratchet wheel 19 which is fixed to said shaft, and a driving pawl 20 which is pivoted to the lever 14. The lever 14 and the pawl 20 are both controlled by a spring 21 which engages the head of the pawl and is suitably mounted upon the shaft 18. 22 designates a second pawl engaging said ratchet wheel and controlled in such engagement by a spring 23, said pawl serving to prevent an overthrow of movement of the operating lever.

The lower series of perforators 23' are arranged in the rear of the casing in positions to perforate from each ticket the dates of the issuing of the tickets, and the direction of travel. The upper series of punches 23' are arranged in positions to perforate the point of destination and the value of fare paid upon each ticket. These punches are of a construction substantially as shown and described in pending application Serial No. 281,750, and it is thought unnecessary to give a minute description of said punches further than to state that they are operated all simultaneously with the operation of the main operating lever 14 through the following devices: 24 designates a series of punch-actuators which are connected to a vertical link 25; the lower series of punch-actuators are thus connected to said link 25, and said series of punches are connected with a slotted pitman 26 by means of an arm 27 that extends from the shaft of the upper one of said actuators 24. The upper series of actuators 24 are connected by a link 28 shown in Fig. 2, and from one of said actuators there extends an arm or crank 29 which carries a pin 30 which projects into the upper bifurcated end of the pitman 26. The pitman is given the necessary movement from a shoulder 31 which is on the inner portion of the main operating lever and the lower end of which pitman rests upon said shoulder. The punched portions of the tickets of the upper punches fall into a small receptacle 32 arranged below the punches—see Fig. 3, while the punched portions of the rearward set of punches fall at the rear of the casing so that the mechanism is kept free from any clogging, all as more fully set forth in the pending application hereinbefore referred to. On the other end of the shaft 18 is a second master gear 17. The total counter 34 shown in Fig. 1, is driven from this master gear through a pinion 33 which is on the arbor of said total counter. This total counter registers the totals of all the fares or tickets issued.

I now refer to an important feature of the invention, namely, the detail counters 35 by means of which the detail fares or tickets are recorded; these are arranged in the present instance in the adjacent compartment 4, and in the present instance consist of six counters corresponding in number to the six different fares or ticket values. These detail counters 35 are on shaft 38 which may be supported in any suitable manner. As shown in the drawings, they are secured to a series of frames or supports 36 and are arranged in a circle which has for its center the shaft 37. The detail counters 35 have each a star wheel or actuator 39 fixed thereto, and as shown in Fig. 1, each of the star wheels is out of alinement with the rest. These star wheels are engaged in a manner presently described, by a finger or actuator 40 which projects from a hub 41 which is mounted on the shaft 37 and has some necessary horizontal movement on said shaft. The hub 41 has a

sleeve 42 extended from it which projects into the hub 43 on the lower end of shifting lever 44, said hub 43 being also mounted on the shaft 37 to have sliding movement thereon in order that it may shift the finger 40 in alinement with any of the star wheels 39. The shifting lever 44 is mounted upon a shaft 45 about at the center of said lever, and the said lever is thus mounted to have sliding movement to the extent of the space or width occupied by the star wheels 39. The upper end of the shifting lever 44 is suitably connected to the horizontal bar 46 to which the fare indicator pointer 47 is attached. This horizontal bar 46 with its pointer 47 is moved horizontally in guide 48 attached in the present instance to the interior of the top of the machine. On the exterior of the top of the machine there is a scale 49 upon which is indicated each fare or ticket value corresponding to the fares or values shown on the tickets illustrated in Fig. 6. On the other side of the scale 49 there is a second scale 50 which indicates the points of destination as corresponding with the points of destination shown on the tickets. These points of destination are separately indicated by means of a pointer 52 which is fixed to an indicator bar 51 which is mounted to slide horizontally to the proper position to indicate said points of destination. The last named indicator 52 is moved by the hand in a manner similar to that illustrated and described in Patent No. 789,333. It will be observed that the pointer 47 which indicates the fares or values of the tickets on the indicator 49, is connected directly with the shifting arm or lever 44, and that said shifting arm or lever controls at its lower end the detail counter-actuating finger 40. It will therefore be understood that when the shifting arm or lever 44 is moved to a position which causes the pointer 47 to indicate a specific fare, the finger or actuator 40 will be moved to the specific detail counter 35 which counts the specific fare or ticket.

In Fig. 1 the fare values are shown in connection with the individual star wheels of each of the detail counters, that is to say, each one of the star wheels 39 of said counters 50 is associated with a specific fare or ticket value inscribed upon the fare indicator 49—Fig. 4. The shifting lever or arm 44 is given the necessary movement by means of an operating lever 53 fulcrumed at 54 and extending 55 through an opening in the front of the casing. The inner end of this operating lever is bifurcated and straddles the arm 44 adjacent to the shaft 45 upon which said arm or lever 44 is slidingly mounted as before stated. It 60 will be understood that the hub 43 on the lower end of the shifting arm 44 receives the hub or sleeve projecting from the hub 41 of the finger 40, and that the opening in the sleeve and hub 41 of said finger is square to conform to 65 the cross section of the shaft 35 so that said

finger may be rotated when said shaft is rotated. The hub of the arm 44 fits loosely around the sleeve or hub of the finger 40 so that it offers no resistance to the free movement of the shaft or the finger, see Fig. 9, 70 Sheet 2. The shaft 37 is rotated the desired extent each time from the master gear 17', an intermediate pinion 55 and a pinion 56, the latter being on the shaft 37. It will be borne in mind that this master gear 17' is on 75 the shaft 18 which is operated through the main actuating lever 14. The diameter of the pinion 33 of the total counter 34 and the diameter of the pinion 56 through which the shaft 37 is rotated, are such that the ratio of 80 movement imparted to the total counter and the detail counters is one-fifth of that of the master gear 17'. The portions of the tickets indicating the direction and which in the present instance consists of the words "Up" 85 "Down" are perforated by a separate punch 23" which is operated from the side of the machine by means of a finger button 23"—see Fig. 7. To punch the word "Up" the finger button is pushed inwardly to its limit 90 while its position is to its outer limit when the word "Down" is to be punched.

Having thus fully described the construction of the machine, I will now detail briefly the operation of issuing a ticket. For example, if a ticket is to be issued to either "New Street" or "Dorset" the fare for such ticket is "1⁰", the shifting lever 53 is moved to actuate the shifting arm 44 which in turn, brings the pointer 47 to a position to indicate 100 1⁰ on the indicator 49, and in the meantime, the finger or actuator 40 is shifted to the position to engage the star wheel 39 of the counter which operates in connection with that particular fare. From Fig. 1, it is seen 105 that this is the lower left hand counter. The pointer 52 is then moved to indicate either "New Street" or "Dorset" on the indicator 50. The main operating lever 14 is then depressed and all of the punches are 110 actuated to punch the tickets at the selected points, the return or upper movement of said lever feeds the ticket so punched, out of the machine, and presents the ticket strip in a position for the punching and issuing of the 115 next ticket.

Having described my invention, I claim:

1. In a machine of the type specified, ticket-feeding mechanism adapted to feed a ticket strip upon which are previously printed 120 a series of uniform tickets, a punch for identifying upon each ticket prior to the operation of the ticket-feeding mechanism, the value thereof, a series of detail counters upon which each class or value of ticket is registered, an 125 indicator to indicate the value of each ticket independently of the ticket itself, and means for simultaneously actuating the indicator to indicate the value of each ticket to be issued and for placing the ticket-feeding 130

- mechanism and a selected counter in operative relation.
2. In a machine of the type specified, ticket-feeding mechanism for feeding a continuous strip of printed tickets, a punch for perforating said tickets to indicate thereon the fare values thereof, a series of detail counters upon which are registered the ticket of each fare or value, means for establishing an operative relation between the ticket-feeding mechanism and a selected detail counter, and means for simultaneously actuating said selected detail counter during the operation of issuing a ticket.
3. In a machine of the type specified, an indicator to indicate the fare values of tickets issued, a series of detail counters to register the tickets issued, a series of punches to punch the fare values upon the tickets as shown on the indicator, and to punch the destination on the tickets, means for feeding tickets from a continuous strip, a total counter to count all the tickets irrespective of their fares or values, and means actuated by the ticket-feeding mechanism for simultaneously actuating one of the detail counters and the total counter.
4. In a machine of the type specified, a series of counters to register the different fares or tickets, an actuating device on the shaft of each counter, a rotating actuator common to all of said counter-actuating devices and movable into operative relation therewith, means for simultaneously indicating a fare or ticket to be registered on a selected counter and for moving said actuator into an operative relation with the actuating device of a selected counter, and means for operating said actuator when so moved.
5. In a machine of the type specified, a series of detail counters grouped around a common axis, an individual-actuating device on the shaft of each counter, said actuating devices being out of alinement with each other, an actuator common to all of said counter-actuating devices and adapted to be shifted into operative relation with the actuating device of any counter selected for operation, means for so shifting said actuator to such position, ticket-feeding mechanism, and means operated thereby simultaneously with the issuance of a ticket to impart movement to said actuator and the counter with which it is placed in operative relation.
6. In a machine of the type specified, a series of detail counters assembled around a common shaft, a total counter, an actuator common to all of said detail counters, means for simultaneously indicating a ticket or fare to be registered and for moving the actuator to a position to operate the counter upon which such ticket or fare is registered, means for perforating the ticket to indicate thereon the fare, ticket-issuing mechanism, and means actuated thereby for operating the perforating mechanism.
7. In a machine of the type specified, a series of detail counters, an actuating device common to all of said counters, an indicator to indicate a fare or ticket to be registered on a selected counter, means for simultaneously moving the pointer of said indicator and the said actuating device, the latter into operative relation with a selected counter, a series of punches to perforate each ticket so indicated and registered, ticket-feeding mechanism, and means operated thereby to actuate said punches.
8. In a machine of the type specified, a series of detail counters arranged around a common axis, an actuating device common to all of said counters, means for moving said actuating device into operative relation with a selected counter, ticket-feeding mechanism, and means actuated thereby in the feeding of tickets to impart movement to said actuating device after the latter has been moved into operative relation with a selected counter.
9. In a machine of the type specified, a series of detail counters, an actuator common to all of said counters, means for moving said actuator to a position to operate a selected counter, an indicator movable to a position to indicate the fare or ticket to be registered on said selected counter, said indicator being actuated simultaneously with the movement of the actuator for the counters, ticket-feeding mechanism, and means operated thereby for actuating the counter actuator in feeding the tickets.
10. In a machine of the type specified, a series of detail counters, a counter-actuating device on the shaft of each of said counters, an actuator common to all of said counters and adapted to be moved into operative relation with the operating device of each selected counter, means for shifting said actuator to such position, an indicator to indicate the fares or tickets registered on the counter selected for operation, a total counter, ticket-feeding mechanism, and means operated simultaneously with the ticket-feeding mechanism for operating simultaneously the selected detail counter and the total counter.
11. In a machine of the type specified, means for feeding tickets, a series of detail counters mounted around the common axis for registering said tickets, means for indicating the value of each ticket issued and registered, an actuating device for obtaining a mechanical relation between the ticket-feeding mechanism and a selected counter, and means actuated by the ticket-feeding mechanism and imparting movement to said actuating device.
12. In a machine of the type specified,

ticket-feeding mechanism, means for indicating the fare of each ticket, means for perforating each ticket to indicate thereon the fare or value of said ticket, means actuated by 5 the ticket-feeding mechanism to perforate the next ticket to be issued, a series of detail counters to register each ticket issued, an actuator common to all of said detail counters, means for moving said actuator to an operative position with a selected counter, and 10 means operated by the ticket-feeding mechanism for imparting movement to said actuator and said selected counter.

13. In a machine of the type specified, 15 means for feeding a ticket strip, perforators independently movable to positions to perforate said tickets, means actuated prior to the ticket-feeding operation for operating said perforators, a series of detail counters 20 upon which are registered the tickets perforated and issued, said counters being actuated simultaneously with the ticket-feeding operation.

14. In a machine of the type specified, 25 means for feeding a ticket-strip, a permanent indicator denoting the fares or values of the tickets, a series of detail counters to register the tickets, mechanism between the permanent indicator and the detail counters by 30 which a ticket of a definite fare or value is indicated, and a definite detail counter is selected, means actuated by the ticket-feeding mechanism for imparting movement to a selected counter during the issuance of a ticket, 35 and a total counter to register the tickets of all the fares indicated and registered on the detail counters.

15. In a machine of the type specified, 40 means for feeding a ticket strip including a main operating lever, an indicator denoting the fares or values of the tickets, a series of detail counters to register the tickets of each fare or value, mechanism placed between said indicator and the detail counters by 45 which a ticket of a definite denomination and a definite detail counter are selected, means actuated by the ticket-feeding mechanism for imparting movement to the selected counter in the issuance of a ticket, a total 50 counter to register all the fares indicated and registered, a series of perforators to perforate the ticket to be issued by the next succeeding operation of the ticket-feeding mechanism, said perforators being actuated by the main 55 operating lever.

16. In a machine of the type specified, ticket-feeding mechanism, a permanent counter to register the total of all of the tickets issued, a series of detail counters to register each specific class of tickets issued, an indicator to indicate the specific values or denominations of the tickets issued, an actuator simultaneously movable with the indicator into operative relation with a selected 60 counter, and means operated by the ticket- 65

issuing mechanism and imparting movement to said actuator and said selected counter to register the tickets so indicated and issued.

17. In a machine of the type specified, mechanism for feeding a strip of tickets, a permanent indicator to indicate the fare values of each ticket, a pointer movable to indicate said ticket values, a perforator movable simultaneously with said pointer to a position to punch a ticket at the selected fare 70 value indicated on said ticket, a series of detail counters to register the different fares so indicated and punched, and a main operating lever which actuates said punches or perforators in one of its movements and feeds the 75 ticket and actuates the detail counter co-operating with each ticket in its reverse operation.

18. In a machine of the type specified, mechanism for feeding a ticket strip, a series 85 of detail counters to register the tickets, means for selecting each counter to register the tickets to be issued, means actuated by the ticket-feeding mechanism to impart movement to the counter-selective mechanism, a total counter, and means actuated by the ticket-feeding mechanism to impart movement to said total counter simultaneously with the movement of a selected detail counter. 90

19. In a machine of the type specified, ticket-feeding mechanism adapted to feed a continuous strip of tickets, a series of detail counters, a shiftable actuator movable to a position to actuate a selected counter, a 100 shiftable punch to perforate a ticket, an indicator to indicate the ticket to be registered on said counter and to be perforated, and means for simultaneously shifting the indicator and the actuator to operative positions. 105

20. In a machine of the type specified, means for feeding a ticket from a continuous strip, punches movable to positions to perforate the tickets at selected points, an indicator to indicate the value of each ticket, a series of detail counters, means movable by the indicator mechanism to positions to engage a selected detail counter, and operating means whereby the punches are operated in one movement of said means and the tickets are fed and the detail counters are operated to register said tickets in the other movement of said operating means. 110

21. In a machine of the type specified, ticket-feeding mechanism for feeding a continuous strip of tickets, a series of detail counters to register each ticket as issued, a punch or perforator to punch each ticket at the selected points prior to its issuance, 125 means engaged by the ticket-feeding mechanism for actuating said punch in one direction of the movement thereof and for actuating the selected counter in the reverse movement thereof. 130

22. In a machine of the type specified, a fare indicator to indicate the value of each ticket issued, a pointer movable along said indicator, a punch to punch each ticket at 5 selected points prior to its issuance, said punch being movable simultaneously with the movement of the indicator pointer, a member movable laterally by said indicator pointer, a series of counters grouped around 10 a common center, a counter actuator movable to position to actuate a selected counter, said counter actuator being movable simultaneously with the movement of the indicator pointer.
- 15 23. In a machine of the type specified, the combination with ticket-feeding mechanism, of a multiplicity of fare counters, selective means for selecting a counter to be actuated to register a ticket to be issued, means movable simultaneously with said selective mechanism to indicate the fare of the counter selected, means actuated by the ticket-feeding mechanism to impart movement to the selected counter through the selective mechanism, a total counter, and means actuated by the ticket-feeding mechanism to impart movement to said total counter.
- 20 24. In a machine of the type specified, the combination with ticket-issuing mechanism, of a series of detail counters grouped around a common axis and each having an operating device on its shaft, an actuator common to all of said counters and by means of which the counters are selected for operation, means for shifting said actuator to an operative position with the operating device of the counter selected, and means actuated by the ticket-issuing mechanism and imparting movement to said actuator and thence to the 25 selected counter.
- 25 25. In a machine of the type specified, the combination with ticket-issuing mechanism, of a series of detail counters to register the tickets issued, an actuator common to all of said counters, an indicator common to all of said counters, an inter-connection between said actuator and said indicator by which they are movable simultaneously to indicate the fare and to select a counter to register such fare, means actuated by the ticket-issuing mechanism to impart movement to the selected counter through said actuator, a series of punches for perforating each ticket prior to its issuance, and means operated from said ticket-issuing mechanism by which 30 said punches are actuated.
- 35 26. In a machine of the type specified, a series of counters arranged around a common axis, an actuator slidably mounted and movable along said axis to be brought into operative relation with any one of said counters, and ticket-feeding mechanism, with intervening means actuated thereby for imparting movement to said actuator to operate the selected counter.
- 40 27. In a machine of the type specified, a series of counters arranged around a common axis, an actuator common to all of said counters and slidably mounted on said axis, means for bringing said actuator into operative relation with any one of said counters, an indicator movable simultaneously with said actuator, ticket-feeding mechanism, and means actuated thereby to impart movement to the selected counter through the 45 actuator.
- 45 50 55 60 65 70 75

In testimony whereof I affix my signature, in presence of two witnesses.

JOHN F. OHMER.
